EXHAUST CONCEALING AND SILENCING DEVICE

Nolan O. Collier, Jr., Montgomery, Ala., assignor
of one-half to Nolan Oliver Collier, Sr., Mont-
gomery, Ala.

Application December 14, 1943, Serial No. 514,266

5 Claims. (Cl. 60—31)

This invention relates to an improved device for concealing and silencing the flaming exhaust gases discharged from the cylinders of a radial internal combustion engine such as is commonly used for driving the propellers of aircraft.

An important object of the present invention is to provide a device of the above kind which is particularly adapted for use in connection with aircraft, and by means of which the exhaust gases are finally discharged in a smooth, quiet stream some distance rearwardly of the aircraft propeller after the flame and much of the pressure of the exhaust gases have been spent, thereby eliminating much of the noise and disturbance of air-flow that accompanies the conventional discharge of exhaust gases outwardly into the wash of an aircraft propeller.

A specific feature of the present invention is the provision of a casing surrounding the engine and the associated exhaust concealing and silencing device, and by means of which air is directed into contact with the outer surfaces of the various parts of the device for cooling purposes.

A further specific object of the present invention is to provide a device of the above kind which is simple and compact in construction, efficient in operation, and otherwise well adapted for meeting the requirements for a successful commercial use.

The present invention consists in the novel form, combination and arrangement of parts hereinafter more fully described, shown in the accompanying drawings and claimed.

In the drawings, wherein like reference characters indicate corresponding parts throughout the several views:

Figure 1 is a view partly in elevation and partly in central longitudinal section, showing an exhaust concealing and silencing device associated with the propeller-driving engine of an aircraft.

Figure 2 is an enlarged fragmentary central longitudinal sectional view showing the major portion of the exhaust concealing and silencing device per se with the casing broken away and the engine omitted.

Figure 3 is a transverse sectional view taken on line 3—3 of Figure 2.

Figure 4 is an enlarged fragmentary detail section taken on the plane of line 4—4 of Figure 2.

Figure 5 is an elevation of the vaned disc initially impinged by the exhaust gases when discharged into the housing of the exhaust concealing and silencing device proper.

Figure 6 is a fragmentary end elevation looking at the rear end of the device shown in Figure 1.

Figure 7 is a fragmentary section taken on line 7—7 of Figure 1.

Figure 8 is a fragmentary section taken on line 8—8 of Figure 2.

5 Figure 9 is an enlarged sectional detail view, partly broken away, showing the manner of mounting and spacing the impellers on the shaft of the present device.

Figure 10 is a transverse section taken on line 10—10 of Figure 2.

Figure 11 is an enlarged fragmentary sectional view, showing details of the yieldable props and braces.

Referring in detail to the drawings, 5 indicates 15 a conventional type of radial internal combustion engine having a forwardly extending drive shaft 6 which carries the usual aircraft propeller, not shown. In accordance with the present invention, each radial cylinder of the engine 5 is provided with a rearwardly extending exhaust pipe 7, and the rear ends of these exhaust pipes 7 are inturned where they connect and communicate with a vertical annular exhaust manifold 8 having a circular series of radial inwardly extending discharge pipes 9 whose inner ends are directed rearwardly in adjacent concentric relation to an axial shaft 10, as indicated at 11. A circular protecting plate or fire wall 12 is vertically disposed directly in front of the manifold 8 and is therefore interposed between the latter and the engine 5 so as to prevent any forward passage of the flaming exhaust toward the engine, as it is discharged from the pipes 9. This plate or wall 12 is provided with a series of peripheral notches, 35 as at 13, to receive the exhaust pipes 7 and aid in effectively mounting said plate or wall 12 in position.

The present device further includes an elongated cylindrical housing 14 whose forward open end is disposed in close proximity to the discharge ends 11 of pipes 9 and is provided with an out-turned annular flange 15 whose inner portion is offset, as at 16. The shaft 10 is disposed axially of and extends rearwardly nearly through the housing 14, and secured on this shaft 10 and arranged within the offset portion 16 of the flange 15 is a vaned disc 17 whose major central portion is provided with a number of radial vanes 18 set at a slight angle, as clearly shown in Figure 4. Thus, the exhaust gases which discharge from the pipes 9 will act upon the blades 18 so as to rotate the disc 17 and become initially broken up by the latter. A series of screw impellers 19 are disposed along the length of the shaft 10 within the housing 14, the same being spaced uniformly

apart by means of spacer sleeves 20 fitted on said shaft between the impellers. Suitable antifriction bearings 21 are interposed between the hubs of the impellers 19 and the spacing sleeves 20 to reduce friction to a minimum, as clearly shown in Figure 9. As the exhaust gases flow rearwardly, they successively impinge upon the impellers 19 for being retarded and broken up, and extending axially from the rear end of the housing 14 is a discharge pipe 22 from which the exhaust gases finally discharge in a steady relatively quiet stream, free of flame and with the blast pressure thereof substantially spent. If desired, the housing 14 may be provided with a forwardly and downwardly extending air intake 23 and similar lateral air intakes 23a for the admission of cool air diagonally of the housing 14 for retarding and cooling purposes. Also, an auxiliary exhaust discharge pipe 24 may extend upwardly and rearwardly from the housing 14 near its rear end portion. Any slightly flaming exhaust gases discharging from this pipe 24 will not be readily seen from the ground by an observer directly below the aircraft.

Disposed in spaced concentric relation to and surrounding the engine 5, exhaust pipes 1, manifold 8, casing 14 and discharge pipe 22 is an outer casing 25 of circular cross section and tapering gradually smaller rearwardly. The rear end of the casing 25 has a central opening through which the rear end of the pipe 22 extends, and the front end of said casing 25 is substantially open. Also, adjacent its front end, the casing 25 is provided with any desired number of louvered air inlets 26 and at its rear end with louvered vents or air outlets 27. Thus, a flow of cool air may enter and pass through the casing 25 so as to contact the outer surfaces of the parts enclosed therein for cooling purposes with respect to said parts. The rearward passage of cool air is also permitted by louvered air passages in the fire wall or plate 12, as at 28. Suitable means is provided for sustaining the casing 25 in proper spaced relation to the housing 14, such as yieldable radial props 29 between the casing 25 and the discharge pipe 22 and radial braces 30 between the under side of the housing 14 and the bottom portion of the casing 25. The props 29 are also of similar yielding construction so that shocks may be cushioned between the parts 14 and 25. Each prop 29 and brace 30 includes a rod *r* having a plunger *a* movable in a cylinder *b* and backed by a compression spring *c* disposed in the cylinder. It will be noted that the pipes 23, 23a and 24 project outwardly through the casing 25, and any suitable means is provided for journaling the shaft 10 axially of the housing 14 including a bearing bracket 31 associated with the rear end of said shaft and affixed to the housing 14.

In operation, the exhaust gases pass from the cylinders of the engine 5 through the exhaust pipes 1 into the manifold 8, whereupon said gases are discharged rearwardly from the radial pipes 9 into the housing 14. These exhaust gases discharging from the pipes 9 initially impinge the vaned disc 17 for being initially retarded and broken up, and this retarding and breaking down operation is repeated as the gases flow rearwardly and successively impinge the impellers 19. The exhaust gases finally discharge from the rear end of the pipe 22 in a flameless condition and in a smooth relatively quiet stream which does not interfere with the wash of the aircraft propeller driven by the shaft 6. Additional discharge of exhaust gases is had through the pipe 24 and re-

tarding and cooling action upon the gases is effected by means of the cool air admitted through the pipes 23 and 23a. Further, the various parts 1, 8, 14, 22 and 24 are effectively cooled by means of the air admitted into and flowing through the casing 25 into contact with the outer surfaces of those parts.

From the foregoing description, it is believed that the construction and operation, as well as the advantages of the present invention will be readily understood and appreciated by those skilled in the art. Minor changes in the details of construction illustrated and described are contemplated within the spirit and scope of the invention as claimed.

What is claimed as new is:

1. In combination with the propeller-driving radial-type internal combustion engine of an aircraft having rearwardly extending exhaust pipes, a vertical annular exhaust manifold disposed rearwardly of said engine and communicating at equally spaced points directly with the outlet ends of said exhaust pipes, said manifold having a circular series of equally spaced and inwardly extending radial discharge pipes provided with rearwardly directed inner ends, an elongated cylindrical housing disposed rearwardly of said manifold coaxially of the latter so that said radial discharge pipes discharge into the forward end thereof, a shaft disposed axially of said housing, the inner ends of said discharge pipes being grouped about said shaft, a vaned disc carried by said shaft at the front end of said housing to be initially impinged by the exhaust gases discharged from said radial discharge pipes, a series of screw impellers mounted on said shaft in spaced relation longitudinally of the latter, and a straight final exhaust pipe extending axially of and rearwardly from said housing, and an outer casing surrounding the engine, the manifold and the housing, said outer casing having a front air inlet and a rear air outlet for permitting flow of cooling air therethrough.

2. In combination with the propeller-driving radial-type internal combustion engine of an aircraft, a vertical annular exhaust manifold disposed rearwardly of said engine and communicating with the exhaust pipes of the cylinders of said engine, said manifold having a circular series of inwardly extending radial discharge pipes provided with rearwardly directed inner ends, an elongated cylindrical housing disposed rearwardly of said manifold coaxially of the latter so that said radial discharge pipes discharge into the forward end thereof, a shaft disposed axially of said housing, a vaned disc carried by said shaft at the front end of said housing to be initially impinged by the exhaust gases discharged from said radial discharge pipes, a series of impellers mounted on said shaft in spaced relation longitudinally of the latter, and a final exhaust pipe extending axially of and rearwardly from said housing, an outer casing disposed in concentric relation to and surrounding the engine, the manifold, the housing and the final exhaust pipe, said outer casing having air inlets and outlets respectively near the front and the rear thereof for permitting the rearward flow of cooling air into contact with the outer surfaces of said manifold, housing and exhaust pipe.

3. In combination with the propeller-driving radial-type internal combustion engine of an aircraft, a vertical annular exhaust manifold disposed rearwardly of said engine and communicating with the exhaust pipes of the cylinders of

said engine, said manifold having a circular series of inwardly extending radial discharge pipes provided with rearwardly directed inner ends, an elongated cylindrical housing disposed rearwardly of said manifold coaxially of the latter so that said radial discharge pipes discharge into the forward end thereof, a shaft disposed axially of said housing, a vaned disc carried by said shaft at the front end of said housing to be initially impinged by the exhaust gases discharged from said radial discharge pipes, a series of impellers mounted on said shaft in spaced relation longitudinally of the latter, and a final exhaust pipe extending axially of and rearwardly from said housing, an outer casing disposed in concentric relation to and surrounding the engine, the manifold, the housing and the final exhaust pipe, said outer casing having air inlets and outlets respectively near the front and the rear thereof for permitting the rearward flow of cooling air into contact with the outer surfaces of said manifold, housing and exhaust pipe, and

5 radially yielding braces and props for sustaining the housing and the outer casing in spaced concentric relation.

5. In combination with the propeller-driving radial-type internal combustion engine of an aircraft, a vertical annular exhaust manifold disposed rearwardly of said engine and communicating with the exhaust pipes of the cylinders of said engine, said manifold having a circular series of inwardly extending radial discharge pipes 15 provided with rearwardly directed inner ends, an elongated cylindrical housing disposed rearwardly of said manifold coaxially of the latter so that said radial discharge pipes discharge into the forward end thereof, a shaft disposed 20 axially of said housing, a vaned disc carried by said shaft at the front end of said housing to be initially impinged by the exhaust gases discharged from said radial discharge pipes, a series of impellers mounted on said shaft in spaced relation longitudinally of the latter, and a final 25 exhaust pipe extending axially of and rearwardly from said housing, an outer casing disposed in concentric relation to and surrounding the engine, the manifold, the housing and the final exhaust pipe, said outer casing having air inlets and outlets respectively near the front and the rear thereof for permitting the rearward flow of cooling air into contact with the outer surfaces of said manifold, housing and exhaust pipe, and

30 a fire wall interposed between the engine and said annular manifold in close proximity to and in front of the latter, said fire wall having a series of peripheral notches receiving the 35 exhaust pipes from the cylinders of said engine.
